[57] CLAIM

The ornamental design for a table base, as shown and described.

DESCRIPTION

FIG. 1 is a perspective view of a table base, showing my new design;

FIG. 2 is a typical side elevational view;

FIG. 3 is a top plan view;

FIG. 4 is a bottom plan view;

FIG. 5 is a cross-sectional view, taken along line 5—5 in FIG. 2;

FIG. 6 is a top plan view of the pad portion, shown enlarged for convenience of illustration; and,

FIG. 7 is a side elevational view of FIG. 6.
